UNITED STATES PATENT OFFICE.

EDWIN J. BURROWS, OF BUFFALO, NEW YORK, ASSIGNOR OF ONE-HALF TO
JAMES B. BAYNES, OF SAME PLACE.

DESIGN FOR A TIRE.

SPECIFICATION forming part of Design No. 32,324, dated March 6, 1900.

Application filed November 16, 1899. Serial No. 737,247. Term of patent 14 years.

To all whom it may concern:

Be it known that I, EDWIN J. BURROWS, a citizen of the United States, residing at Buffalo, in the county of Erie and State of New York, have invented and produced a new and original Design for Tires, of which the following is a specification, reference being had to the accompanying drawings, forming a part thereof.

This design relates to the configuration or transverse outline of elastic or cushion tires.

The accompanying drawing is a sectional perspective view of a portion of a cushion-tire embodying my design.

5 A represents the straight bottom of the base portion of the tire.

B B are the sides of the base portion, which diverge upwardly from the bottom.

C is the arched tread portion, and C' C' are the sides of the tread portion, which converge upwardly and merge into the semicircular face of the tread portion.

D D are ribs arranged on opposite sides of the tire at the junction of the base portion with the tread portion. These ribs project 25 laterally from the upper widest portion of the base portion and are convex on their upper sides and concave on their lower sides. These ribs form approximately angular projections which extend along both sides of the tire 30 and which have downwardly-curving convex upper sides and hollow or concave lower sides.

What I claim is—

The design for an elastic tire, substantially 35 as shown and described.

Witness my hand this 10th day of November, 1899.

EDWIN J. BURROWS.
